PRICE CARD HOLDER FOR PRICE TAG MOLDINGS

William N. Beddar, Rte. 1, Box 337, Wayzata, Minn.

Filed Dec. 5, 1962, Ser. No. 72,737

Term of patent 14 years

(Cl. D1—3)

FIG. 1.

FIG. 2.

FIG. 1 is a front perspective view of a price card holder for price tag moldings embodying my design; and FIG. 2 is a side elevational view of the same.

I claim:

The ornamental design for a price card holder for price tag moldings, as shown.
